No. 839,369.

PATENTED DEC. 25, 1906.

A. DITNER.
WATER GAGE.
APPLICATION FILED DEC. 21, 1903.

UNITED STATES PATENT OFFICE.

ALBERT DITNER, OF MÜLHAUSEN, GERMANY, ASSIGNOR OF ONE-HALF
TO EMIL ENGASSER, OF COLMAR, ALSACE, GERMANY.

WATER-GAGE.

No. 839,369.

Specification of Letters Patent.

Patented Dec. 25, 1906.

Application filed December 21, 1903, Serial No. 186,067.

To all whom it may concern.

Be it known that I, ALBERT DITNER, a subject of the German Emperor, residing at Mülhausen, in the Province of Alsace, in the 5 German Empire, have invented new and useful Improvements in Water - Gages, of which the following is a specification.

The devices usually employed for automatically preventing the escape of steam and 10 water on breakage of the glass of water-gages on steam-boilers usually consist of ball, clack, or swing valves located direct in the steam and water passages of the gage. On 15 the glass breaking these valves are closed by the rush of steam occasioned. The current of steam necessary to close the valves may, however, be caused without breakage of the glass by a variation of pressure in the boiler without the engineman observing it. Fur- 20 thermore, such valves located direct in the steam and water passages greatly contribute to the accumulation of mud and hard de- 25 posits. Both these circumstances may lead to the most serious consequences, as the gage then no longer gives a correct indication.

The purpose of my invention is to overcome the defects referred to by providing the valves outside the steam and water passages 30 of the water-gage and by employing steam direct from the boiler to close the valves on the glass being broken.

My invention is illustrated by the accompanying drawing, in which the figure shows in elevation and part section one form of the 35 new gage.

a is a casing provided with a thread *h*, by which means it can be screwed into the cock attachment *u*. *b* is a small piston working easily within the casing *a*. This piston is 40 screwed to the rod *e*, which is guided in the narrow neck *y* of the casing *a* and terminates in a conical valve *c*. *f* is a spring coiled around the piston-rod *e* and bearing against the neck *y* above and the piston *b* below. The neck *y* is perforated by a number 45 of holes *l*. *s* is a nipple projecting from the casing *a* and over which the nut *z* is screwed for the purpose of effecting a steam-tight joint between the pipe *d* and nipple *s*. The 50 said tube *d* may either lead into the passage of the cock attachment *u* or to the boiler direct. *v* is a three-way cock for blowing off

on breakage of the glass. Such a device is provided at either end of the water-gage.

Its operation is as follows: As long as the 55 glass remains intact the pressure in the wa- ter-gage, by reason of the perforations *l* in the neck *y*, acts upon the top of the piston *b* and counterbalances the pressure on the lower face of the piston, transmitted from the boiler 60 through the tube *d*, and under the action of the spring *f* the piston *b* will remain in its lower- most position. The passage of water and steam through the bores of the seatings *u* will therefore be wholly unobstructed. If, how- 65 ever, the gage-glass *w* breaks, the pressure on the top of the piston *b* ceases suddenly, and the boiler-pressure acting on the lower face of the piston forces the latter upward until the valve *c* sits in its seat *t*, formed in the passage lead- 70 ing to the water-gage glass *w*, whereby the escape of water and steam is prevented.

The device at the top of the gage-glass acts in exactly the same manner as that at the bottom, being the inverted counterpart 75 of the latter.

The device is suitable for application to ordinary water-gages for boilers and other like apparatus in which the level of the liq- 80 uid has to be continually watched.

Having thus described my invention, what I claim as new, and desire to secure by Letters Patent, is—

In water-gages a device for automatically preventing the escape of steam and water on 85 the gage-glass breaking, comprising a hollow casing, a seating and a pipe *d*, the hollow cas- ing communicating at one end direct with the bore of the seating, and at the other end with the pipe *d* through which pressure is trans- 90 mitted directly from the apparatus on which the gage is mounted, and a piston located within the casing, balanced in favor of the pressure on the seating-bore side, and on breakage of the gage-glass effecting closing of 95 the passage from the bore to the glass, all substantially as described.

In testimony whereof I have signed this specification in the presence of two sub- 95 scribing witnesses.

ALBERT DITNER.
